UNITED STATES PATENT OFFICE.

JOHN FINDLATER SIMPSON, OF SCUNTHORPE, ENGLAND, AND WILLIAM CARMICHAEL
PEEBLES, OF EDINBURGH, SCOTLAND.

GAS GOVERNOR.

Application filed December 1, 1924, Serial No. 753,340, and in Great Britain December 3, 1923.

This invention relates to gas governing devices for maintaining, as far as possible, constant pressure at the points of use under varying demand conditions.

5 A device according to the invention comprises an automatic or station governor with means for increasing the delivery pressure with increased demand, and a differential governor in series with the automatic governor and contrived to set up a constant differential pressure across the valve of the automatic governor and thus prevent pressure changes from affecting the discharge per unit area of valve opening through the 10 automatic governor.

The figure of the accompanying drawing is a sectional side elevation of a device according to the invention.

As shown, the bell or controlling element 20 A of the automatic governor sustains the spindle B carrying the valve beats C, D which control the flow of gas through the valve apertures E, F in the gas conduit. To isolate the bell from the pressure zone 25 around the valve beats, a small inner bell G is arranged around the spindle B.

From the spindle B there extends upwards a rack H meshing with a quadrant P pivoted at L and fixed to a lever K that carries a curved track J upon which is adapted to run a trolley M carrying a set of weights N by addition or removal of one or more of which the pressure of operation may be readily adjusted. It will be seen that, as 30 the bell A falls or rises, the rack H partially rotates the quadrant P whereby the lever K is rocked and the track J tilted so that the trolley M travels in one direction or the other along the track and the moment of the 35 weight N about the pivot L is increased or decreased, such moment being applied as a load to the bell A through the medium of the quadrant P and rack H.

The bell A and valve C, D are partly 40 counterpoised by a weight suspended by a chain V from a quadrant lever T pivoted at S and fixed to a second quadrant R engaging the rack H.

The space within the bell A is connected 45 with the conduit M¹ for gas at outlet pressure by a pipe V¹ in which is interposed a valve Y¹.

It is understood that, the interior of the bell A being connected to the conduit by the 50 pipe V¹, with increase in the demand the

bell A falls so that the valve C, D is opened further. With the descent of the rack H the trolley M moves along the curved track J and the moment of the weight N acting on the bell is increased as aforesaid. Thus, the 60 pressure increases as the valve C, D descends until a state of balance is reached between the upward and downward efforts on the bell A.

The differential governor disposed in series with the automatic governor comprises a bell Q¹ movable within a sealed casing P and sustaining a valve K¹ anterior to the valve C, D and of the same area as the under side of the bell Q¹. The interior of the 70 bell Q¹ is in communication with the conduit on the inlet side of the valve K¹. The space within the interior of the casing P¹ communicates by way of a pipe S¹ (fitted with a valve T¹) with a point of the conduit 75 on the delivery side of the automatic governor valve C, D.

As the upward lift of the bell Q¹ and the downward pressure on the valve K¹ neutralize one another, changes in the inlet pressure are without effect on the bell Q¹ or 80 valve K¹.

As the weight of the valve K¹ and bell Q¹ are only partly balanced, the tendency of the valve K¹ is to open; in other 85 words, the differential governor is loaded to balance the differential pressure.

As the pressure beyond the automatic governor valve C, D increases, increased pressure acting on the upper surface of the 90 bell Q¹ tends to depress the bell Q¹ and open the valve K¹, allowing more gas to pass.

As, however, the pressure beyond the valve K¹ builds up, it reacts on the underside of the valve K¹ and brings about a stabilization 95 of pressure which continues as long as the demand remains constant.

In the claims the term "bell" is to be understood as covering any equivalent therefor.

What we claim is:—

1. In a gas governing device, in combination with a gas conduit, an automatic governor including a valve interposed in said conduit, a controlling element connected to 105 said valve, a curved track horizontally pivoted between its ends, a weight movable on said track, operative connections between said track and said controlling element whereby said track is tilted and said weight 110

2
 moved to increase or decrease the load on
 said controlling element as said valve moves
 further from or nearer to its closed position,
 and a controllable connection from a point
 of said conduit beyond said valve to the
 under side of said controlling element,
 and a differential governor in series with
 said automatic governor and comprising a second
 valve within said conduit anterior to said
 first mentioned valve, a bell connected
 to said second valve and open on its under
 side to a point of said conduit anterior to
 said first named valve, and a controllable
 connection between the upper side of said
 bell and a point of said conduit beyond said
 first named valve.

2. In a gas governing device, in combination
 with a gas conduit, conjoined valve
 beats interposed in said conduit to control
 the flow of gas through said conduit, a
 spindle common to said valve beats, a bell
 sustaining said spindle, means for isolating
 said bell from the pressure zone around
 said valve beats, a transmission element ex-
 tending upwards from said bell, a pivoted
 quadrant operatively connected with said
 transmission element, a lever fixed to said
 quadrant, a curved track fixed to said lever
 and tiltable on rocking movement of said
 quadrant effected by endwise movement of
 said transmission element, a weighted trolley
 movable along said track when said
 track is tilted, and a controllable connec-
 tion from a point of said conduit beyond said
 valve beats to the interior of said bell.

3. In a gas governing device, in combination
 with a gas conduit, an automatic gov-
 ernor including a valve interposed in said
 conduit and a controlling element connected
 to said valve, a track horizontally pivoted
 between its ends, a weight movable on said
 track, and operative connections between
 said track and said controlling element
 whereby said track is tilted and said weight
 moved to increase or decrease the load on

said controlling element as said valve moves
 further from or nearer to its closed posi-
 tion, a controllable connection from a point
 in said conduit beyond said valve to the
 under side of said controlling element, a 50
 differential governor in series with said au-
 tomatic governor and comprising a second
 valve within said conduit anterior to said
 first mentioned valve, a controlling element
 connected to said second valve and open on
 its under side to a point of said conduit
 anterior to said second valve, and a controll-
 able connection between the upper side of
 said second named controlling element and
 a point of said conduit beyond said first 60
 named valve.

4. In a gas governing device, in combina-
 tion with a gas conduit, an automatic gov-
 ernor including a valve interposed in said
 conduit and a controlling element connected 65
 to said valve, a rack connected to said con-
 trolling element, a curved track pivoted
 horizontally between its ends and opera-
 tively connected to said rack, a weighted
 member movable along said track when said
 track is tilted on its pivot on endwise move-
 ment of said rack, a controllable connection
 from a point of said conduit beyond said
 valve to the under side of said controlling
 element, a differential governor in series 75
 with said automatic governor and compris-
 ing a second valve within said conduit, an-
 terior to said first mentioned valve, a con-
 trolling element connected to said second
 valve and open on its under side to a point
 of said conduit anterior to said second valve,
 and a controllable connection between the
 upper side of said second named controlling
 element and a point of said conduit beyond
 said first named valve. 85

In testimony whereof we have signed our
 names to this specification.

JOHN FINDLATER SIMPSON.

WILLIAM CARMICHAEL PEEBLES.
